UNITED STATES PATENT OFFICE.

JAMES MADISON CARAWAY, OF LONGMONT, COLORADO.

BEET-TOPPER.

SPECIFICATION forming part of Letters Patent No. 764,423, dated July 5, 1904.

Application filed September 14, 1903. Serial No. 173,140. (No model.)

To all whom it may concern:

Be it known that I, JAMES MADISON CARAWAY, a citizen of the United States, residing at Longmont, in the county of Boulder and 5 State of Colorado, have made certain new and useful Improvements in Beet-Toppers, of which the following is a specification.

My invention is an improvement in the class of apparatus or machines adapted for 10 removing the tops from harvested beets.

A distinguishing feature of the invention is the provision of an endless horizontal traveling belt provided with a spring-coil for holding the beets while being topped and an oscillating knife or cutter, which is adapted to 15 make a draw cut and is operated by the same means as the belt, as hereinafter set forth.

The details of invention will be understood from the following description and the accompanying drawings, in which—

Figure 1 is an elevation of the rear side of my improved apparatus. Fig. 2 is a plan view of the same. Fig. 3 is an end view. Fig. 4 is a longitudinal section on the line 4 25 4 of Fig. 2. Fig. 5 is a detail section of the endless traveling belt with its spring-coil attachment. Fig. 6 is a side view illustrating the operation of the knife or cutter.

The working parts of the apparatus are attached to and supported by a frame 1, supported on runners 2. Upon the frame 1 is supported the platform 3 and on the runners the platform 4. (See Fig. 2.) Two vertical standards 5 support a broad bar or timber 6, which is arranged horizontally. At the ends of the said bar 6 are journaled rollers 7 and 8, the latter having a shaft 9, which is provided with two cranks 10 and 11, for the purpose presently stated. A broad belt 12 runs 35 on the aforesaid pulleys 7 and 8 and is provided with device 13 for spacing and holding the beets while being topped. The same consists of a spiral coil of spring-wire whose convolutions or turns are secured to the belt 40 by means of a strip of leather or wire 14. The knife or cutter 15 is a straight-edge blade arranged parallel to the outer side of the bar 6 and journaled slidably on a pivot 16, that projects laterally from said bar. The knife 45 is provided with a lengthwise slot 17 to re-

ceive the said pivot, and it is connected with the crank 11 of the shaft 9.

The operation of the parts so far described is as follows: An operator stands upon the platform 3 and turns the crank 10 of shaft 9, whereby the pulley 8 is rotated, and the belt 12 caused to travel in direction of the arrow, Fig. 2. Another operator, standing upon the smaller and lower platform 4, places the beets upon the belt 12 in a position transverse of the same and parallel to each other, so that the tops overhang the outside of the belt. The smaller ends of the beets are laid between the convolutions of the spring-coil 13 and are thus spaced apart and in most cases held 60 or compressed so they retain their due position while passing under the knife. The latter is oscillated and also reciprocated so that it makes a draw cut. It will be further seen that it acts against the side or edge of the bar 70 6 in such manner that the latter forms a straight-edge or practically an opposing shear-blade. It will be further seen that since the knife is retracted or drawn to the right, as in Figs. 1 and 6, after making its cut it thereby 75 passes out of the way of the untopped beets, which are still advancing on the belt, and when the knife is ready to descend again the beets have been carried up to it, so that a new 80 line of untopped beets lies directly below the knife. As shown in Figs. 1 and 5, the convolutions of the spring 13 are necessarily separated more widely while passing around the pulleys 7 and 8. This enables beets to be 85 placed between the convolutions at the left-hand end of the apparatus, Figs. 1 and 2, and in the case of the larger beets their ends will be clamped and held while being topped, but will be released upon reaching the right-hand end of the apparatus, where they discharge into a lateral chute 18.

The beets to be topped are preferably deposited in a box or tray 19, arranged at the left-hand end of the apparatus. This box is supported by a broad bar 20, which is held 95 slidably in a keeper 21, attached to the frame-piece 2. The box is brought out when required for use, so as to clear the spring-coil 13. When the apparatus is not in use, the box is pushed back as far as practicable be- 100

neath the belt. It will be noted that the box 19 is in close proximity to the small platform 4, so that the operator may conveniently remove beets therefrom to the belt 12.

5 The base portions 1 of the frame of the apparatus are, in effect, skids or runners, which are beveled or sloped at one end, as shown, so that the apparatus may be conveniently hauled from one point to another in the field, 10 where the beets are collected in piles.

Having thus described my invention, what I claim as new, and desire to secure by Letters Patent, is—

1. The improved beet-topper comprising a 15 suitable frame, an endless traveling belt and pulleys upon which it is mounted, a knife provided with a lengthwise slot and pivoted through said slot parallel to and near one side of the belt, and means for operating the belt 20 and knife simultaneously, whereby the latter is caused to make a draw cut, substantially as described.

2. The improved beet-topper comprising a suitable frame, an endless traveling belt and 25 pulleys upon which it runs, a knife having a longitudinal slot and pivoted to the frame parallel and near to one side of the belt, a crank-shaft which operates one of the said pulleys and is connected with and also operates the 30 knife in the manner shown and described.

3. The improved beet-topper, comprising a suitable frame, pulleys mounted therein, an endless traveling belt arranged on the latter,

and a spiral spring-coil secured to the belt for use in spacing and holding the beets while being topped, and a suitable knife for severing the tops, substantially as described. 35

4. The improved beet-topper comprising a suitable horizontal frame, pulleys mounted thereon, and an endless traveling belt which 40 runs on said pulleys, a spiral spring-coil whose convolutions are secured to the belt and normally separated by a space adapted to receive the tips of beets, the convolutions being more widely separated at the ends of the apparatus 45 so as to receive and discharge beets in the manner described.

5. The improved beet-topper comprising a suitable horizontal frame, pulleys mounted at the ends of the frame, an endless belt traveling on said pulleys, a device attached to the belt and extending longitudinally thereof and arranged adjacent to the edge of the same, whereby it is adapted for holding the tips of beets while their larger portions or heads are 55 supported upon the contiguous plane surface of the belt, and a cutter for severing the tops of the beets, the same being located contiguous to the edge of the belt which is farthest from the aforesaid device for holding the tops 60 of the beets.

JAMES MADISON CARAWAY.
